(57) **CLAIM**

I claim the ornamental design for a pontoon kicker motor mount, as shown and described.

DESCRIPTION

FIG. 1 is a front perspective view of a pontoon kicker motor mount showing my new design; the perspective view from the adjacent front corner being a mirror image thereof; FIG. 2 is a front perspective view thereof, the perspective view from the adjacent front corner being a mirror image thereof;

FIG. 3 is a rear perspective view thereof, the perspective view from the adjacent rear corner being a mirror image thereof;

FIG. 4 is a rear perspective view thereof, the perspective view from the adjacent rear corner being a mirror image thereof;

FIG. 5 is a rear elevation view thereof;

FIG. 6 is a front elevation view thereof;

FIG. 7 is a top plan view thereof;

FIG. 8 is a bottom plan view thereof;

FIG. 9 is a side elevation view thereof;

FIG. 10 is an elevation view from the side opposite FIG. 9;

FIG. 11 is a bottom perspective view thereof; and,

FIG. 12 is a top perspective view thereof.

Broken lines, illustrate structure and/or features which form no part of the claimed design.
